Primary Examiner — W. A. Teddy Falloway*Assistant Examiner* — Melissa Adriane Santos(74) *Attorney, Agent, or Firm* — Xuan Zhang(57) **CLAIM**

The ornamental design for a column headlight, as shown and described.

DESCRIPTION

FIG. 1 is a perspective view of a column headlight showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the drawings illustrate portions of the column headlight that form no part of the claimed design.
